US00D928199S

(12) **United States Design Patent** (10) **Patent No.:** **US D928,199 S**
Mazlish et al. (45) **Date of Patent:** **** Aug. 17, 2021**

- (54) **MEDICATION DELIVERY DEVICE WITH ICONS** H04N 2005/4456; H04N 2005/44565;
H04N 2005/44569; H04N 2005/44573;
H04N
- (71) Applicant: **Bigfoot Biomedical, Inc.**, Milpitas, CA (US) (Continued)
- (72) Inventors: **Bryan Mazlish**, Palo Alto, CA (US); **Sabine Kabel-Eckes**, Mountain View, CA (US); **Jeff Boissier**, San Jose, CA (US); **Bethany Leigh Salmon**, San Jose, CA (US)
- (73) Assignee: **Bigfoot Biomedical, Inc.**, Milpitas, CA (US)
- (**) Term: **15 Years**
- (21) Appl. No.: **29/642,766**
- (22) Filed: **Apr. 2, 2018**
- (51) LOC (13) Cl. **14-04**
- (52) U.S. Cl. **USPC D14/489**
- (58) **Field of Classification Search**

- Primary Examiner — Christian P. McLean
(74) Attorney, Agent, or Firm — TraskBritt
- (57) **CLAIM**
- The ornamental design for a medication delivery device with icons, substantially as shown and described.

DESCRIPTION

FIG. 1 is a front view showing an embodiment of the design. FIG. 2 is a front view showing an embodiment of the design. FIG. 3 is a front view showing an embodiment of the design; and, FIG. 4 is a front view showing an embodiment of the design. The broken lines illustrate portions of the medication delivery device that form no part of the claimed design.

1 Claim, 4 Drawing Sheets(58) **Field of Classification Search**
